UNITED STATES PATENT OFFICE

119,668

DESIGN FOR A WINGED INSOLE

Horatio S. Lyness, Lynn, Mass., assignor to United
Shoe Machinery Corporation, Borough of
Flemington, N. J.

Application October 3, 1939, Serial No. 87,484

Term of patent 3½ years

To all whom it may concern:

Be it known that I, Horatio S. Lyness, a citizen of the United States, residing at Lynn, in the county of Essex and Commonwealth of Massachusetts, have invented a new, original, and ornamental Design for a Winged Insole, of which the following is a specification, reference being had to the accompanying drawing, forming part thereof.

The drawing is a perspective view of a winged insole showing my new design.

The dominant feature of my invention relates to the decorative row of perforations extending along a curved line at the junction of the shank and wing portions of the insole and resides more particularly in the specific relation of the semi-circular perforations to that line and to the adjacent curved edge of the wing of the insole.

I claim:

The ornamental design for a winged insole, substantially as shown and described.

HORATIO S. LYNES.
